UNITED STATES PATENT OFFICE

ANATOLE EDOUARD DECOUFLÉ, OF PARIS, FRANCE.

APPARATUS FOR MANUFACTURING CIGARETTE-TUBES.

SPECIFICATION forming part of Letters Patent No. 349,785, dated September 28, 1886.

Application filed January 16, 1886. Serial No. 188,741. (No model.) Patented in France August 14, 1885, No. 170,636.

To all whom it may concern:

Be it known that I, ANATOLE EDOUARD DECOUFLÉ, machine builder, residing at Paris, France, have invented an Improved Apparatus for Manufacturing Unpasted Cigarette-Tubes, (for which I have obtained Letters Patent in France, dated August 14, 1885, No. 170,636,) of which the following is a specification.

10 The invention hereby sought to be secured by Letters Patent consists in a novel apparatus for manufacturing cigarette paper tubes without the use of any paste or size, and thus avoiding the inconveniences heretofore met 15 with in the employment of ordinary pasted cigarettes.

The unpasted cigarette-tube, which may be of any length and diameter, is closed along one of its generating-lines by clasps or hooks 20 or by folding or rolling two, three, four, or more thicknesses of paper embodied within each other, in the manner hereinafter fully described.

The improved machine effects a longitudinal fastening by means of a flange or seam, having the shape of a flattened tube, which is formed by the rolling or winding into each other of the two edges of the paper sheet or band; and while this fastening or closing 30 method may be applied outside of the cigarette-tube without departing from the principle of my invention, yet I much prefer to apply the same internally, as it then affords all the advantages, which chiefly consist in preventing the accidental disconnection of the 35 rolled and flattened edges, from any cause, and rendering any additional closing at the ends of the cigarette-tube unnecessary; but the means I have devised for the manufacture of 40 my cigarette-tubes with internal longitudinal fastening will be readily understood by the inspection of the accompanying drawings.

In the drawings, Figure 1 is an elevation, and Fig. 2 a plan view, of the apparatus. Fig. 45 3 is a vertical section, whereby the inner arrangement of the apparatus may be understood; and Figs. 4 to 9 are cross-sections taken on the lines 4 4, 5 5, to 9 9, respectively. Figs. 10 to 12 are sections of the paper tube in its 50 progressive stages.

p is a paper band, the width of which corresponds to the size of the complete tube when

unwound, including of course the parts that are to be taken up by the joint obtained by rolling the edges within each other. The paper *p*, wound upon roller *P*, is first directed between guide-rolls *a* *a'*, one of which, *a*, has a curved convex generating-line, and the other, *a'*, a correlative concave curve. From thence it will at once enter a curvilinear convergent 60 channel, *b*, which causes the edges of the paper band gradually to rise and then to be bent down inward at the extreme end of the channel, thus assuming in section the shape indicated in Fig. 10. The turning down of the 65 edges *x* *x'* is caused in the first place by the outline of the channel, which itself is imperceptibly and gradually turned down, and in the second place by the portion *c*, which is entirely closed, and forms a sequel of the channel, a rib, *c'*, being fitted therein, as shown in Fig. 7, which, as aforesaid, is a section on line 7 7. The tube thus prepared is supported by a stem or rod, *d*, concentric with the forming mechanism, and is only released thereby 75 when completed. The tubular part *c* only ends when the two edges of the paper *x* *x'* are entirely turned down, as shown in Fig. 11. At that instant the inner projections, *x* *x'*, enter a truncated cone-shaped funnel, *e*, which may 80 or may not be wound spirally. Within this device the paper edges are rolled together, so as to form a spiral, *x*, as shown in Fig. 12.

Funnel *e* is arranged within a hollow provided for the purpose in the rod *d*, so that the 85 whole of the device is limited by the periphery of said rod *d*, as shown in Fig. 8, which is a section on line 8 8, Fig. 1, as aforesaid. Beyond funnel *e* spiral *x* is flattened in the middle by a roll, *g*, turning within a hollow, 90 *f*, cut lengthwise in rod *d*, and being V-shaped, as shown in Fig. 9. The roll *g* is hung in the lower part of a stem, which is surrounded by a spring, as shown in Fig. 3. The fold made by the spring-pressure of roll *g* remains unchanged until the paper reaches the pulling devices, which simultaneously complete the fastening. These devices comprise a grooved roller, *h*, under which a small wheel, *m*, with a plain or serrated surface, is located within a recess in rod *d*, and, lastly, another plain wheel, *m'*, is superposed above the second drawing-roller, *h'*. The pressure exerted by roller *h* and wheel *m* upon the squeezed spiral *x* re-

sults in a goffering of the several thicknesses of paper, so that the same are incorporated within each other and constitute an internal junction fold, which, although of a hardly-perceptible thickness, is exceedingly strong. The function of wheel m' is to support rod d , in combination with the lower roller, h' , which does not, however, hinder this roller h' from assisting the other roller, h , in the feeding operation.

The feeding of the tube is effected by lengths or half-lengths, or in a continuous manner. In the latter case—namely, when the feeding is continuous, suitable cutters may be arranged at or near the terminal of rod d for the purpose.

$s s' s^2 s^3 s^4$ are the supports of the several parts of which the apparatus consists. They are all, as shown, suitably attached to table t . The said apparatus may, however, vary in its main parts, according as it is, or is not, in connection with a cigarette-machine.

I have before stated that the pressure of the drawing-roller h and wheel m upon the spiral of the tube, no matter whether the same is inside or outside, has the effect of incorporating

within each other the paper thicknesses incorporated within said spiral. The paper may, if desired, be used in a moist condition.

I claim—

1. In apparatus for manufacturing cigarette-tubes, the combination of the curvilinear channel b with the inner rod, d , tubular channel c , and rib c' , against which the edges of the endless paper band p are turned, as specified. 30

2. In apparatus for manufacturing cigarette-tubes, the rod or spindle d , combined with the tubes b c , rib c' , and funnel e , as described. 35

3. The combination of the squeezing-roller g with the rod d , having recess f and funnel e , as specified. 40

4. The pulling or drawing rollers h h' , combined with the rod d , provided with groove f , funnel e , roller g , and with the wheels m and m' , as specified. 45
